UNITED STATES PATENT OFFICE.

HENRIK J. AMBRUSON, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

GAS-PRODUCER.

1,252,612.

Specification of Letters Patent.

Patented Jan. 8, 1918.

Application filed January 25, 1915. Serial No. 4,112.

To all whom it may concern:

Be it known that I, HENRIK J. AMBRUSON, a citizen of the United States, residing at Worcester, in the county of Worcester and 5 Commonwealth of Massachusetts, have invented a new and useful Improvement in Gas-Producers, of which the following, together with the accompanying drawings, is a specification.

10 The present invention relates to gas producers, and has particular reference to the introduction and distribution of the blast of air, or air and steam, used to support the combustion of the fuel contained within the 15 main shell, or fuel supporting section, of devices of this class.

The herein described embodiment of my invention, is, in the present instance, shown and described in its application to a specific 20 construction and arrangement of producer parts involving the assemblage and support of the blast devices and the fuel section upon the ash support or pan of the producer, which construction forms the subject matter 25 of an invention fully set forth and described in an application for Letters Patent filed by E. A. W. Jefferies, December 14, 1914, Serial No. 877,004. But while my invention is shown thus applied, by reason of its peculiar 30 adaptability as an important, useful and valuable improvement upon the invention covered by the aforesaid application of Jefferies, yet my invention is not to be limited in its use to the above or any other particular 35 construction, except in so far as is determined by the scope of the annexed claims.

The essential features of my invention are 40 fully set forth in the following description, and illustrated in the accompanying drawings, in which—

Figure 1 is a vertical sectional view of the lower portion of a gas producer embodying my invention.

Fig. 2 is a plan view of the same, portions 45 thereof being shown in a section taken in the plane of line 2--2, Fig. 1.

Fig. 3 is a detail view in perspective of the adjacent ends of two segments of an annular blast box.

50 Like reference characters refer to like parts in the different figures.

The numeral 1 indicates the lower portion of a gas producing chamber, inclosed within the wall or shell 2 which constitutes the fuel

supporting section of the producer. The 55 lower end of said shell, in accordance with approved practice, opens into a concentric 60 as support or pan 3, shown in the present instance as rotatable, and in accordance with the aforesaid invention of Jefferies, 65 serving for the support of the shell 2 through the interposition of a hollow spider casting 4, having a plurality of radial blast arms 5, the outer ends of which are disposed in supporting relation to the lower 70 end of said shell. The casting 4 is supported upon a hollow casting 6, disposed concentrically upon the floor or bottom of the ash pan, and providing a communicating blast 75 passage between the interior of said spider casting and a blast inlet passage 7 opening upwardly through the supporting floor of the producer and centrally through the bottom of said ash pan.

The hollow spider casting 4 preferably 75 has a central aperture, not shown, with respect to which a spaced circular cap 8 is effective in providing for an annular upwardly directed jet of blast through the center of the bed of fuel. Each hollow blast 80 arm 5 is formed along its top wall with an elongated opening or slit 9, with respect to which a spaced rectangular cap 10 is effective in providing for a pair of upwardly directed jets of blast through the fuel bed 85 in substantially radial planes.

In accordance with the present invention, the structure made use of in rigidly and securely connecting the lower end of the shell 2 with the outer ends of the blast arms 5, 90 takes the form of a sectional annular member indicated as a whole by the numeral 11, the same presenting an extended upper wall 12 preferably inclined so as to lie normal to the flaring wall 2, thereby facilitating the 95 erection thereon of the brickwork 13 constituting the inner lining of said wall. Said annular member 11 comprises a plurality of segmental sections, corresponding in number to the number of radial blast arms 5, 100 in the present instance shown as three in number. For convenience of manufacture and assemblage, each section comprises a pair of trough-like segments 14, 15, substantially U-shaped in cross section, and disposed 105 end to end, with their adjacent ends in communication through a joint preferably formed by a U-shaped flange 16 on the segment 14,

Figs. 2 and 3, which is received within the trough of the segment 15. The segments 14 and 15 have suitable upper and lower flanges 17 which are bolted, riveted, or otherwise secured to the inner surface of an annular sheet metal shell 18 forming the outside of the wall 2 and depending below the brick-work 13 of said wall. The three elongated segmental chambers 19 thus formed by each pair of segments and the coöperating portions of the shell 18 covered thereby, are closed at their ends by the blanked off opposite ends 20 cast in each segment, Fig. 2, whereby the necessity for a close fit between the segments of the member 11 exists only with respect to one half of the total number of points at which the ends of adjacent segments meet.

The segment 14 of each section of the member 11 has an inwardly extended radially disposed nipple 21, leading from the chamber 19, and forming a connecting passage between said chamber and one of the blast arms 5. Each of said blast arms carries, beyond its open outer end, with which the associated nipple makes a joint, a shelf or projection 22, disposed in supporting relation to said nipple, and to which said nipple is suitably secured by bolts, rivets or the like. The support of the shell 2 upon the ends of the blast arms 5 is thereby attained.

The lower walls 23 of the several segments 14 and 15 have downwardly opening blast apertures 24 therethrough; said walls lie in a plane closely approaching the horizontal, and overhang the lower portion of the shell 18. By reason of this disposition of the walls 23, the tendency of the adjacent ash or incandescent fuel in the horizontal zone of said apertures 24 to be crowded by the weight of the superposed fuel bed into close contact with the under side of the walls 23, is materially reduced, with the result that a well defined space or pocket 25 is maintained in the neighborhood of said apertures 24, permitting an unimpeded passage of the blast therefrom.

The construction above described affords an ideal distribution of the blast to the bed of fuel. In addition to the distribution afforded by the spider casting 4, fully described above, an annular series of blast jets are delivered adjacent the wall 2 of the producer, whereby all portions of the fuel bed are subjected to a substantially uniform permeation by the blast. The division of the annular member 11 into a plurality of separated segmental blast chambers 19, corresponding in number to the number of radial blast arms 5, insures the delivery of the blast entering each of said arms to one third of the fuel bed surface. For if the member 11 presented a continuous annular blast chamber, the tendency would be for the greater portion of the blast to escape therefrom at

a point or points where the fuel bed presented the least resistance to the passage of the blast through the apertures 24.

By the present construction each blast arm 5 and its communicating chamber 19 delivers substantially one third of the blast, whether or not the apertures 24 of its chamber are more or less obstructed by the ash or fuel than the apertures 24 of another chamber 19.

I claim,

1. In a gas producer, a fuel shell, blast distributing means for the fuel therein, comprising hollow radially arranged arms having perforations for the delivery of blast within said shell, and a hollow member conforming to the wall of said shell and in communication with the outer ends of said arms, and means for rotating said shell and said blast distributing means in unison. 85

2. In a gas producer, a rotating ash support, a plurality of hollow blast arms spaced above and supported from the center of said ash support and rotatable therewith, a hollow annular blast distributing member carried by the ends of said arms and in communication therewith, and a fuel-containing shell carried by said member. 90

3. In a gas producer, a rotatable ash support having a central blast opening, a plurality of hollow blast arms communicating with said opening above said ash support, a hollow annular blast distributing member carried upon the ends of said blast arms and communicating therewith, and a fuel-containing shell superposed upon said member. 95

4. In a gas producer, a shell inclosing a bed of fuel, blast distributing means therein, comprising a member coöperating with the wall of said shell to provide a chamber on the inner side thereof, said member providing a bottom wall for said chamber in a plane substantially normal to the wall of said shell, with a series of delivery apertures opening downwardly through said bottom wall, and means for rotating said member and said shell in unison. 105

5. In a gas producer, a shell inclosing a bed of fuel, blast distributing means therein, comprising a hollow member conforming to the wall of said shell and having on its under side a wall extending inwardly of said shell, said wall providing the blast delivery means from said member to said shell, whereby the obstruction of the blast by the mass of fuel is prevented, and means for rotating said member and said shell in unison. 115

6. In a gas producer, a shell inclosing a bed of fuel, blast distributing means therein comprising a hollow member conforming to the wall of said shell and overlying a portion of the same, whereby a space substantially free from fuel is formed below said member, said member providing a series of 125

delivery apertures opening into said space, and means for rotating said member and said shell in unison.

7. In a gas producer, a shell inclosing a bed of fuel, blast distributing means therein comprising a hollow member disposed centrally of said shell and having a plurality of hollow arms, and a member conforming to the wall of said shell and composed of a plurality of independent hollow sections each communicating with one of said arms, means for delivering blast from each of said sections, and means for rotating said members and said shell in unison.

15 8. In a gas producer, a shell inclosing a bed of fuel, blast distributing means therein comprising a hollow member disposed centrally of said shell and having a plurality of hollow radial arms, and an annular member conforming to the wall of said shell and composed of a plurality of independent hollow segmental sections each communicating with one of said arms, means for delivering blast from each of said sections, and means 25 for rotating said members and said shell in unison.

9. In a gas producer, a shell inclosing a bed of fuel, blast distributing means therein, comprising a hollow member disposed centrally of said shell and having a plurality 35

of outwardly extending arms, a member secured to the wall of said shell, and composed of a plurality of independent hollow sections each communicating with one of said arms, means for delivering blast from each 35 of said sections, and means for rotating said members and said shell in unison.

10. In a gas producer, an ash pan, a member supported centrally upon said ash pan and provided with a plurality of radially 40 extending arms spaced above said ash pan, a hollow blast distributing member supported by the ends of said arms, and a fuel-containing shell superposed upon said hollow member.

11. A gas producer, comprising a rotating fuel-containing shell, a blast distributing means for the fuel in said shell, rotatable in unison with said shell, said blast distributing means comprising a plurality of radial 50 hollow arms within said shell having blast distributing openings therein, and a hollow annular member in communication with the outer ends of said arms.

Dated this twenty-second day of January 55
1914.

HENRIK J. AMBRUSON.
